UNITED STATES PATENT OFFICE.

MORRIS M. WHITAKER, OF NYACK, NEW YORK.

DESIGN FOR A DOOR KNOCKER.

Application filed July 2, 1927. Serial No. 22,658. Term of patent 14 years.

To all whom it may concern:

Be it known that I, MORRIS M. WHITAKER, a citizen of the United States, and a resident of Nyack, county of Rockland, State of New York, have invented a new, original, and ornamental Design for Door Knockers, of which the following is a specification, reference being had to the accompanying drawing, forming part thereof.

Fig. 1 is a front elevation of a door knocker embodying my design;

Fig. 2 is a side elevation thereof.

I claim:

The ornamental design for a door knocker, as shown.

MORRIS M. WHITAKER.
